UNITED STATES PATENT OFFICE.

AXEL VALDEMAR CLORIUS, OF COPENHAGEN, DENMARK.

VALVE.

985,146.

Specification of Letters Patent. Patented Feb. 28, 1911.

Application filed October 24, 1906. Serial No. 340,421.

To all whom it may concern:

Be it known that I, AXEL VALDEMAR CLORIUS, a subject of the King of Denmark, residing at Copenhagen, Denmark, have invented certain new and useful Improvements in Valves, of which the following is a full, clear, and exact description.

The present invention relates to valve mechanism, and more particularly to those in which the valve is automatically operated by thermo-sensitive devices, the object of the invention being to provide a simple, economical, compact and effective device in which injury to the parts is prevented when, after the valve has become seated, the temperature acting on the thermo-sensitive device continues to increase; and to provide a seat-valve which will be cheap, simple and effective in operation. Briefly stated, these objects are attained by providing a cone-shaped valve adapted to seat against a partition in the valve casing, a resilient body being interposed between the valve and the thermo-sensitive device, which resilient body is compressed when, after the valve is seated, further movement of the thermo-sensitive device or a part thereof is had.

The invention will be better understood by reference to the accompanying drawing, illustrating a vertical section through the mechanism, and wherein *a* is a valve casing provided with a perforated partition *s*. Arranged in line with the perforation in said partition is an elongated tubular extension *k* secured at one end in a perforated nut *m*, screwed into said casing *a*, and at its other end to a member *l*. Arranged within said extension *k* is a valve-stem *d* one end of which engages in a perforation in valve *b* which is adapted to obturate the perforation in partition *s*. A resilient body, here shown as a coiled spring *c*, encircles said valve-stem and bears against valve *b*. The lower end of the valve stem *d* is secured to one end of a suitable thermo-sensitive device. As here shown, said stem *d* is connected to one end of a rubber tube *h*, the other end of which tube is immovably connected to a perforated block *n* which extends into said extension *k*. A chamber *e*, arranged in the room or fluid the temperature of which is to be regulated, contains any suitable fluid which

will expand under the influence of heat, and a conduit *g* connects this chamber with the interior of the tube *h* via the perforation 55 in block *n*. A series of metallic rings *j* encircles said tube *h* to prevent lateral expansion thereof. When, therefore, the fluid in chamber *e* is caused to expand under the influence of heat, the tube *h* is 60 caused to elongate and to seat valve *b* against partition *s*. Should the temperature still increase the continued elongation of the tube *h* would result in the compression of spring *c*, the valve being thus pressed 65 somewhat more firmly on its seat, without, however, damaging the device. A decrease in temperature will result in the contraction of said tube *h*, an expansion of spring *c* and—if the cooling progresses to a sufficient extent—the unseating of valve *b*.

It is found that with the cone-shaped valve herein employed, a more effective obturation can be secured than could be effected with the piston valves heretofore used 75 with which it was difficult to secure a tight closure and which were, besides, more complicated and expensive.

What is claimed is:

In a device of the character described, 80 the combination of a valve casing provided with a valve seat, a valve adapted to be seated thereon, an elastic tube adapted to confine a fluid subject to variations of pressure, non-yielding rings surrounding said tube for restricting the expansion of the latter in a longitudinal direction, resilient means for transmitting the longitudinal movement of said tube to said valve to operate the latter in response to variations of 85 said fluid pressure and a tubular extension for inclosing said valve operating means, and a stuffing box on said extension having an adjustable plug to which said flexible tube is secured whereby said movable parts 90 may be adjusted.

In witness whereof I have hereunto set my hand in the presence of two witnesses.

AXEL VALDEMAR CLORIUS.
